UNITED STATES PATENT OFFICE.

WILLIAM B. MERKEL, OF NEW YORK, N. Y., ASSIGNOR TO JOHN S. S. FULTON, OF FULLERTON, PENNSYLVANIA.

FURNACE.

939,526.

Specification of Letters Patent.

Patented Nov. 9, 1909.

Application filed December 14, 1907. Serial No. 406,530.

To all whom it may concern:

Be it known that I, WILLIAM B. MERKEL, of New York, in the county of New York and State of New York, have invented certain new and useful Improvements in Furnaces; and I do hereby declare the following to be a full, clear, and exact description of the invention, such as will enable others skilled in the art to which it appertains to 10 make and use the same.

In the practical operation of furnaces equipped with mechanical stokers it has been found that the parts within the furnace soon wear or burn out because of the intense heat to which they are subjected. This is especially true of the grate bars and the risers on which they are mounted when inclined or shaking grates are employed, while the movable parts entering into the 15 means by which the grates and ashes receptacle are operated are liable to become ineffective and necessitate frequent repairs or substitution of parts. The heat is transmitted through the back wall of the fuel hopper with the frequent result that the coal therein fuses and adheres to the walls of the hopper and prevents its proper and uniform discharge therefrom. When this fusing occurs the attendant is required to 20 dislodge it by poking or barring or the fused fuel, soon becomes a burning mass and the hopper back is destroyed. A similar difficulty is encountered at the lower or back end of the furnace walls and the sides 25 thereof extending for several inches above the grate surface. At the former point the ashes and clinkers tend to adhere to the walls, not only preventing the proper operation of the dumping and moving grates, but 30 whenever these clinkers are removed by the use of a hammer or sledge, as is necessary every few weeks, the amalgamation of the clinkers to the walls is so intense that the fire brick walls, being the weaker, a portion 35 thereof is always destroyed in removing the clinkers, requiring frequent renewing of the walls. This is not only troublesome, but exceedingly expensive. But the greatest 40 source of annoyance and expense is the constant destruction of the grate bars which support, and are at all times in direct contact with, the burning fuel. Without efficient protection, or as at present constructed and in practical operation, mechanical stokers of the inclined grate type re-

quire a renewal of grate bars approximately four or five times a year, due to their being destroyed by the fire.

The primary object of my present invention is to overcome these difficulties and provide effective means for preserving the integrity of the parts as against the action of the heat by a system of water circulation which will include supplying cooling water to both the movable and stationary fuel 65 grates, the adjacent walls of the furnace and the wall of the fuel hopper.

A further object is to connect one grate to another and lead cooling water to and from the different parts in multiple, so that 70 should any unforeseen contingency arise where it would be desirable to cut out the water or cooling supply to any of the different portions protected, it may be done without affecting the others or impairing their 75 efficiency. This is effectually accomplished by having a separate supply and outlet leading to and from the different parts with shut-off valves fore and aft. For instance, the moving grates are fed with an independent supply of water, a shut-off valve being provided in the pipes leading to and from them, so that in case of a defect developing or a pipe bursting in the moving grates, or in the zone between the entrance and shut-off valves, this portion of the water cooling 80 system can be cut out by closing these valves without affecting the other water cooled portions. Another system with independent 85 shut-off valves leads to the fixed or stationary grate; another to the side risers which extend above the grates and act as a protection to the side walls of the furnace; another extends to the lower, or back furnace wall, and still another to the back wall of 90 the fuel supply hopper.

A further object of the invention is to incorporate the cooling water system with the boiler feed and to provide means whereby the cooling system may be continuously supplied whether or not water is being fed to the boiler.

In the accompanying drawing Figure 1 is a view partly in section and partly in side elevation showing a furnace equipped with a grate and stoker mechanism embodying my invention, a water tube boiler being shown mounted above the fire box in the usual or any preferred manner. Fig. 2 is a front elevation. Fig. 3 is a detail view showing 10 11

the pipe connections between the respective grate bars of the two series thereof, and Fig. 4 is a detail view showing the construction of one of the grate bars.

Referring to the drawings 1 designates a furnace having an inclined grate 2, a dumping grate 3 at the lower end thereof controlled by a handle 3^a, and a coal hopper 4 at a point in its front wall near the top of the grate.

10 The grate proper comprises two separate series of bars, one series being fixed, that is, mounted upon stationary side risers, and the other series having its grate bars interleaved with those of the fixed series and mounted upon movable risers, all of the bars of both series collectively forming the fuel supporting surface. The series of fixed bars is indicated by 27, Fig. 1, and one of the stationary side risers on which these fixed bars are mounted is indicated by 38. The series of movable bars is designated by 23 and one of the risers for supporting this series is shown at R. The risers R are mounted at their upper and lower ends upon pivoted gear segments R', R². The stoker actuating devices impart a rocking action to the upper gear segment R' and this action is transmitted by the riser R to the lower gear segment R² with the result that the grate bars 23 are bodily moved back and forth intermediate the fixed bars 27. The means for actuating the moving grate bars forms no part of this invention and need not be described. The only essential of the actuating mechanism so far as concerns the risers R is that it shall oscillate the gear segment R' to slowly move the bars 23 relatively to the fixed bars 27 and thus advance the fuel down the inclined grate. A water tube boiler 6 is shown mounted above the grate 2. Through a pipe 7 and branch 8 water is supplied to the boiler, the pipe 7 being designed to constitute the supply for a battery of boilers. From branch 8 a pipe 9 leads to the boiler, a valve 10 being shown in pipe 9. A pipe 12 connects branch 8 with the cooling system supply 13, a valve 14 in pipe 12 having its stem 15 extending downwardly and equipped with a hand wheel 16 in reach of the furnace attendant. From the top of pipe 13 is shown a pipe 17 extending rearwardly beside the boiler and entering the latter at its rear end where the water is coolest. This pipe is 50 provided with a check valve 18.

10 The water supply pipe 13 is shown extending down to a point approximately in line with the lower end of grate 2. Arranged parallel therewith is a pipe 19 in communication with pipe 13 and controlled by inlet valve 20, and having an outlet valve 20^a. This pipe 19 is shown in communication with the lowermost grate bar 21 of the series 23 of movable grates. As will be seen 55 by reference to Fig. 3 the respective grate

bars of the moving series as well as those of the stationary series are in communication with each other so that the water entering the lowermost movable grate bar 21 will pass through it and successively into and 70 through each of the moving bars to the uppermost one 24 and thence through pipes 25 and 26 into the boiler. Thus with valve 10 closed, as it always will be, the feed water must pass down to the furnace before it can 75 enter the boiler. Pipe 19 hangs freely from its point of connection to pipe 13 and thus it may swing sufficiently to compensate for the movement of the grate bars.

15 The grate bars of the stationary series 27 are supplied with water by branch 28 of pipe 13, the connections between the respective grate bars of this series being, as shown in Fig. 3, substantially the same as those of the moving grates. From the top fixed 80 grate bar 29 a pipe 30 leads to pipe 31, the latter terminating in pipe 26 leading to the boiler.

20 28^a designates the inlet valve and 30^a the outlet valve by which the circulation through 90 the fixed grates is controlled.

I provide an extremely simple, cheap and durable method of connecting the water supply from one grate to the other in both the moving and stationary series of grate bars 95 as well as a simple, and thoroughly reliable method of providing means for the water to flow through the front portions of the grate bars themselves. It must be understood that it is only the front or inner portion A (Figs. 100 1 and 4) which comes in direct contact with the burning fuel and is the only portion of the grate bar that requires protection. As long as this front portion remains intact the remainder of the grate bar is practically 105 indestructible from the action of the furnace heat. To accomplish this I bend an iron pipe in the manner shown in Fig. 4 by the dotted lines and indicated at B. To one end of this pipe I attach an elbow C. The pipe 110 is made sufficiently long to extend the full length of the grate and the grate is preferably constructed to extend the full width of the furnace. The pipe is laid in the mold in place of a sand core and the grate cast 115 around it. While it is possible to construct these grate bars of all cast iron, using a sand core to provide the hole for the passage of the water, yet this construction is extremely unreliable, as cast iron is of very low tensile 120 strength, brittle and not suited for withstanding the boiler pressures to which these grates are at all times subjected. In providing a set for a furnace, every other one 125 is cast with the elbow C at the opposite end from the preceding one. The reason for this will be apparent by reference to Fig. 3 which shows in detail the method in which the water supply is connected from one grate bar to the other.

The holes D at the ends of the grate as shown in Fig. 4 are provided for bolting to the side risers. The spaces E are slots through the grates for the admission of air 5 in addition to that which enters between the grates.

I have shown the rear wall 32 of the coal hopper 4 of hollow formation to constitute a water jacket supplied by pipes 13 and 33, 10 34 designating the outlet from the water jacket to pipe 31, and 33^a and 34^a, respectively, the inlet and outlet valves.

Practice has demonstrated that in the use of an inclined grate having a dumping grate 15 at its lower end, the clinkers and ashes, as they collect near the bottom of the inclined grate, fuse on the hot walls above the dumping grate, seriously interfering with its action. To overcome this I have provided the 20 furnace wall at the rear of the fire box and just above the dumping grate 3 with a transverse orifice 35 in communication at one end with pipe 36 leading from pipe 13 and having a shut-off valve 36^a and at the other end 25 with pipe 26 through branch 37 having a shut-off valve 37^a. By this means there is provided a "water back" having the effect of keeping the rear wall of the fire box cool and preventing clinkers from adhering 30 thereto. Provision has also been made for protecting the side walls from clinkers fusing to them, which seriously interferes with the operation of the moving grates and causes the rapid deterioration of the walls. 35 This is accomplished by constructing the fixed or stationary side risers so that they extend several inches (sufficient to cover the zone in which clinkers adhere to the walls) above the level of the grate area and include 40 the portion exposed to the action of the fuel in the water cooling system. To this end the fixed or stationary grate supports or side risers 38 are shown in communication with supply pipe 13 through pipe 13^a, the 45 latter having a branch pipe 13^b extending to the lower end of the side-riser; the right side-riser having its outlet 40 at its upper end extending across the top of the fuel hopper 4 and discharging into pipe 26. The 50 left side-riser also has an outlet 39 at its upper end, which discharges into the pipe 40. Both the right and left side-risers are provided with means for cutting out the water supply in case of accident; right side- 55 riser by the inlet valve 13^c and outlet valve 40^a and left side-riser by the inlet valve 13^d and outlet valve 39^a. By this construction the side-risers perform a dual function, that of supporting the stationary or fixed grates, 60 and acting as a protection for the side walls of the furnace.

Assuming that water is being fed to the boiler from supply pipe 7, and that valve 10 is closed, and valve 14 open, the course of 65 the water before reaching the boiler is down

through pipes 13 and 19 to the two series of grates, the side-risers, furnace back and back wall of the coal hopper, and then through pipe 26 to the boiler. If, however, feed to the boiler is cut off and valve 14 is closed by 70 manipulation of hand wheel 16, then under this condition the circulation of water in the grates and complementary parts causes the check valve 18 to open and draws water from the boiler through pipe 17 and then 75 into the cooling system 13, 19 etc., the circulation continuing as before but more slowly as it is induced only by the upward movement of the water heated in its passage through the grates, side-risers, etc. It will 80 be understood that the furnace is equipped with suitable means for stoking the fuel, but as any preferred means may be employed I have not shown or described this feature.

Practice has demonstrated that a furnace 85 equipped with my improvements will effect thorough combustion while maintaining the integrity of the mechanical elements entering into the construction and operation 90 of the grate.

A feature of my invention is that it provides for supplying cooling water to the grate bars of both series of grates, that is the series of moving grates as well as the series of stationary grates. Water cooled stationary grates are, of course, well known; there is no difficulty in forming them with passage-ways through which cooling water may flow. Likewise a moving grate, the individual rocking members of which form an inclined automatic stoker, is well known in art, the Roney stoker being the most extensively used. But I am not aware of any practical automatic stoker in which the moving grate, as well as the alternate stationary 100 grates, are supplied with cooling water, although many efforts have been made to accomplish that purpose. In automatic stokers of the Roney type the moving grate bars are mounted upon pivots to permit the 105 bars to turn axially. This is known as the "gate movement". Now it is obvious that any means for supplying cooling water to moving grates must fulfil certain requirements. The tubes through which the water 110 flows must permit of the movements of the grate bars, either by their own flexibility or that of their connections to the moving grates, and when the water is intended to be conducted to the boiler from the grate, these tubes and their joints must be capable of withstanding boiler pressure. The impossibility of satisfying these requirements in pivoted grate bars is fully realized in the 115 art. Their oscillating motion would necessitate using a flexible hose for conducting the water to and from the grates or providing flexible joints or couplings at their points of connection. That neither of these 120 devices would withstand the furnace heat 130

and the boiler pressure is apparent. I overcome these difficulties by dispensing with the pivotally mounted grate bars and employing bars which are rigid upon their supporting 5 risers and so mounting and reciprocating the risers that the series of grate bars move bodily back and forth, the individual bars always co-acting with the alternate stationary bars to form the fuel supporting surface. 10 To these moving bars cooling water is conducted through iron pipes. The vertically disposed pipe 19 from which the water enters the grates is secured at its top only, leaving the lower end free to swing sufficiently 15 to compensate for the reciprocation of the series of moving grate bars. The pipe 25 (Fig. 2) which is similarly connected, furnishes the outlet for the water from the grates to the boiler. I thus provide 20 effective means for cooling by water circulation both series of grates in an automatic stoker, and I am enabled to supply the cooling water at boiler pressure, there being no loose joints to permit of leakage. 25 I am aware that grates of the class to which mine relates have heretofore been used in which the movable members arranged alternately with the fixed bars do not oscillate upon pivots but reciprocate or move bodily. 30 These movable elements, however, do not form part of the fuel supporting surfaces, but are merely pushers to advance the fuel. I am also aware of a construction in which both of two sets of grate bars reciprocate 35 and are water cooled. Such a construction, however, renders very difficult the adjustment of the grate movement to insure the proper relative reciprocations. Furthermore this construction necessitates a great 40 deal of mechanical work without any corresponding advantage as compared to the type to which my invention relates and in which one series of grate bars is stationary.

While I have pointed out the fact that the 45 absence of loose joints in the cooling system enables me to supply water thereto at boiler pressure, yet it will be understood that my invention is not limited to, nor is the success of the stoker dependent upon, the use of 50 cooling water at boiler pressure, since the water may be supplied to the cooling system at city main pressure and after leaving the system be pumped into the boiler at boiler pressure.

55 I claim as my invention:—

1. In a furnace, a grate having fixed and movable bars, means for bodily moving said movable bars as a unit relatively to said fixed bars, said movable bars having water-tight passages therein, and connections between said movable bars.

2. In a furnace having a grate comprising alternately arranged fixed and movable grate bars, means for bodily moving said movable 65 bars back and forth in the spaces intermed-

iate said fixed bars, and means for supplying cooling water to both series of grate bars.

3. In a furnace having a boiler and feed water supply and a grate comprising alternately arranged fixed and movable bars, 70 means for bodily moving said movable bars, a cooling water circulating system in which both movable and fixed bars are included, and means for conducting the feed water to and through said circulating system before 75 its entrance to the boiler.

4. In a furnace having a boiler and a grate comprising alternately arranged fixed and movable grate bars, means for bodily moving said movable bars, a cooling water circulating system in which the fixed and movable bars are included, means for conducting cooling water from the boiler through said circulating system, and means for returning the cooling water to the boiler from the circulating 85 system.

5. In a furnace having a boiler and feed water supply, and a grate comprising alternately arranged fixed and movable grate bars, means for bodily moving said movable 90 bars, a cooling water circulating system in which both the fixed and the movable bars are included, means for conducting the feed water to and through said circulating system before its entrance to the boiler, and means 95 automatically actuated on the cut off of said feed water supply for conducting water from the boiler through said circulating system.

6. In a furnace equipped with a boiler, an 100 inclined grate comprising two series of step grate bars having water tight passages extending therethrough, one series being fixed and the other movable, their respective bars being alternately arranged, risers supporting said movable grate bars and forming therewith one rigid unit, means for reciprocating said risers, side risers supporting said fixed grate bars and forming therewith a second rigid unit, the bars of the two units 110 of fixed and movable grate bars being interleaved, each grate bar of the moving series being in water tight communication with the other grate bars of its series, and each grate bar of the fixed series being in water tight 115 communication with the other grate bars of the fixed series, and means for supplying cooling water to said two series of grate bars.

7. A furnace having a boiler and feed water supply and stoking mechanism having a coal hopper provided with a water jacket, in combination with an inclined grate comprising alternate fixed and movable bars, a cooling water circulating system in which the water jacket of said hopper and said 120 grate bars are included, and means for conducting the feed water to said water jacket and grate bars before its entrance to the boiler.

8. A furnace equipped with a boiler and 130

- stoking mechanism having a coal hopper provided with a water jacket, in combination with an inclined grate comprising alternate fixed and movable bars, a cooling water circulating system in which said water jacket and said grate bars are included, and means for conducting water from said boiler to said water jacket and grate bars.
9. A furnace having a boiler and feed water supply and stoking mechanism including a coal hopper provided with a water jacket in combination with an inclined grate comprising alternate fixed and movable bars, a cooling water circulating system in which said water jacket and said grate bars are included, means for conducting the feed water to said water jacket and grate bars before its entrance to the boiler, and means automatically actuated on the cut-off of said feed water supply for conducting water from the boiler to said water jacket and grate bars.
10. In a furnace equipped with a boiler the combination of an inclined grate comprising alternate fixed and movable bars, means for conducting cooling water to both sets of bars, a dumping grate at the lower end of said grate, and a water back in the rear wall of the fire box adjacent said dumping grate, a feed water supply for said boiler, a cooling water circulating system in which said water back and grate bars are included, and means for conducting the feed water to said water back and grate bars before its entrance to the boiler.

11. In a furnace equipped with a boiler the combination of an inclined grate comprising alternate fixed and movable bars, means for conducting cooling water to both sets of bars, a dumping grate at the lower end of said grate, and a water back in the rear wall of the fire box adjacent said dumping grate, a cooling water circulating system in which said water back and grate bars are included, and means for conducting water from the boiler to said water back and grate bars.
12. In a furnace equipped with a boiler, an inclined grate, a dumping grate at the lower end thereof, and a water back in the rear wall of the fire box adjacent said dumping grate, a feed water supply for said

boiler, a cooling water circulating system in which said water back is included, and means automatically actuated on the cut-off 55 of said feed water supply for conducting water from the boiler to said water back.

13. In a furnace, an inclined grate comprising a series of hollow fixed grate bars, and a series of hollow movable grate bars 60 alternating with the fixed bars, side-risers on which said fixed bars are mounted, said bars terminating at their fuel supporting edges within the width of said side-risers, means for conducting cooling water through 65 both series of bars, and means for conducting cooling water through said risers.

14. In a furnace, a series of fixed grate bars, and side-risers on which said bars are mounted, said bars terminating at their fuel 70 supporting edges within the width of said side-risers, means for conducting cooling water through said risers, and independent means for conducting cooling water through 75 said bars.

15. In a furnace, two series of grate bars, alternately arranged, one series being fixed and the other movable, a pipe extending through each of said series and entering its respective bars successively at opposite ends 80 and lying adjacent their fuel supporting edges, and means for conducting cooling water through said pipes.

16. In a furnace having an inclined grate comprising two series of grate bars, one 85 series being fixed and the other bodily movable, and having the bars of one series alternating with those of the other, and means for bodily reciprocating the movable bars in horizontal planes, each of said series having 90 its respective bars hollow adjacent their fuel supporting edges to form water tight passages and connected at opposite ends with the next bar of the series, and means for conducting cooling water to each of said 95 series.

In testimony whereof, I have signed this specification in the presence of two subscribing witnesses.

WILLIAM B. MERKEL.
